UNITED STATES PATENT OFFICE.

BERNARD D. EILERS, OF UTICA, NEW YORK.

TAKE-DOWN POCKET-KNIFE.

No. 929,295.

Specification of Letters Patent.

Patented July 27, 1909.

Application filed September 8, 1908. Serial No. 452,072.

To all whom it may concern:

Be it known that I, BERNARD D. EILERS, of Utica, in the county of Oneida and State of New York, have invented certain new and useful Improvements in Take-Down Pocket-Knives; and I do hereby declare that the following is a full, clear, and exact description thereof, which will enable others skilled in the art to which it appertains to make and use the same, reference being had to the accompanying drawings, and to the characters of reference marked thereon, which form part of this specification.

The object of my invention is to provide a clasped knife, having means for easily removing and replacing the blade by way of repairing or otherwise, the same not requiring the services of a mechanic or a multiplicity of tools.

Figure 1 shows a knife of my present improved construction in partial taken-down or disassembled condition. Fig. 2 is an enlarged cross-sectional view through the locking mechanism provided in one end of the handle. Fig. 3 is an enlarged sectional view through the blade pivot. Fig. 4 is a similar view to Fig. 3 of a modified form of construction. Fig. 5 is a longitudinal sectional view taken on the center line. Fig. 6 is a similar view to that shown in Fig. 1 of a modified form of construction. Fig. 7 is a similar view of still another modified form of construction.

Referring to the reference letters and figures in a more particular description, 10, 10 indicate the two parts of the handle, which receive therebetween at one end the hinged end of the blade 11, and longitudinally thereof, at the back, the back spring 12. The back spring 12 is mounted on a pin 13 and engages with an angular notch on the pivotal end of the blade, as is common in clasp knives. At the end of the handle which receives the blade 11, is provided the hinge pin 14, which is secured rigidly in one handle part as to one end, and after passing through the blade is provided with a screw-threaded portion 14^a engaging in a screw-threaded opening 14^b in the other handle part. At the opposite end from the pivot 14 the parts of the handle are adapted to be detachably secured together by the combined lock and spring cam 15. This part 15 is adapted to be secured to one of the parts 10 by being provided with a headed pivot 15^a extending through an

opening in the liner 10^a. The part 15 is also provided with a stud 15^b having radial bits adapted, when in open position, to enter the opening 16 in the liner 10^a of the other handle part. With one of the handle parts 10, the springs 12 and the blade 11 assembled in the position shown in Fig. 1, the other handle part 10 may be applied and secured at the pivot end by rotating it around the pivot until the two parts are drawn sufficiently close together by operation of the screw-thread. When in this position, the opening or eye 16 is slipped over the stud 15^b. The cam piece 15 is then rotated to throw the bits of the stud 15^b crosswise of the general longitudinal position of the opening 16, whereby the two parts of the handle are securely locked together, and, at the same time, the cam face of the part 15 throws outwardly the adjacent end of the spring 12, putting it under tension, whereby its opposite end serves on the angular shank of the blade to hold the blade in open or closed position in a well known manner of clasp knives. The cam piece 15 is provided with a notch or shoulder as shown which engages the end of the spring 12 in such a manner that each part serves as a lock for the other unless considerable force is applied to disengage them.

As shown in Figs. 1 and 2, the part 15 may be provided with an eye 15^d for the attachment of a chain. In case this form of construction is used, the chain may be used as a means, in lieu of a wrench, for rocking the position of the part 15 in locking or unlocking. The eye 15^d and the chain, however, may be omitted, in which case the part 15 may assume the form shown at 20 in Figs. 6 and 7, in which case it will be preferably operated by a special wrench. In order more particularly to secure a sufficient thickness to secure an efficient screw-thread, at the blade end the liners are bent or turned back on themselves, as indicated at 10^b, and another piece 17 interposed, around which the edges of the part 10^b are folded, thus providing a metal end and boss of sufficient thickness to provide an effective mounting for the pivot.

In the form of construction shown in Figs. 4 and 7, in lieu of the screw-thread 14^a on one end of the pivot there is provided a T-head 21 adapted to be passed through a slot-like opening 22 in the lining of the opposite member of the handle when the two parts of

the handle are arranged in position substantially at right angles to each other. To lock the two parts of the handle securely together, after inserting the head in the opening, the 5 two parts are brought into parallel position.

In the modified form of construction shown in Figs. 6 and 7, the bits of the locking stud 20^a are arranged at right-angular positions, as compared with those of the construction shown in Fig. 1, and this change requires the receiving opening 24 in the other part of the handle to also be arranged differently; that is to say, extending longitudinally of the handle.

15 It is evident that as to the construction shown in Figs. 1 and 2 without any tool, and as to the construction shown in the other figures with a very simple special tool, any one can readily take apart the knife and replace 20 a worn or broken blade without being especially qualified as a mechanic or provided with a multiplicity of tools, and in a very short period of time. This would enable any ordinary merchant to supply and place in 25 position, if desired, repair blades at little cost.

It is evident that other modifications and changes in and from the construction herein

described may be made without departing from the invention hereinafter claimed.

What I claim as new and desire to secure by Letters Patent is:

1. The combination in a take-down clasp knife of a blade, a separable two-part handle, a spring interposed between the handle parts, a spring tensioning cam pivotally mounted upon one of the parts and having a bitted stud adapted to engage with and secure the other part, substantially as set forth.

2. The combination in a clasp knife of the handle parts, the blade, the spring interposed between the handle parts and mounted on a pivot intermediate its length, a cam for tensioning the spring pivotally secured on one of the parts, means for detachably securing the handle parts together at each end, one of such means consisting of a headed projection mounted on and rocking with the cam, substantially as set forth.

In witness whereof, I have affixed my signature, in presence of two witnesses, this 26th day of August 1908.

BERNARD D. EILERS.
